UNITED STATES PATENT OFFICE.

JAMES H. GREEN, OF BROOKLYN, NEW YORK.

SUPPORTING AND PRESERVING TELEGRAPHIC CONDUCTORS.

SPECIFICATION forming part of Letters Patent No. 275,195, dated April 3, 1883.

Application filed October 27, 1882. (No model.)

To all whom it may concern:

Be it known that I, JAMES H. GREEN, of Brooklyn, in Kings county, and State of New York, have invented a new and useful Improvement in Supporting and Preserving Telegraphic Conductors, of which the following is a specification.

The object of the present improvement is to provide for ridding telegraphic conductors of moisture when they are laid or arranged in conduits.

To this end the improvement consists in the combination, with a box, trough, or pipe, telegraphic conductors arranged therein, and supports for the telegraphic conductors, provided with openings, of means whereby air may be caused to circulate through the box, trough, or pipe.

The improvement also consists in the combination, with a number of telegraphic conductors, of a box, trough, or pipe containing the said conductors, a number of supports for the said conductors, arranged within the box or trough or pipe, openings being provided in the supports and between the supports and the box or trough or pipe for the circulation of air, and means whereby air may be caused to circulate through said box, trough, or pipe.

The improvement also consists in the combination, with a wooden box or trough adapted to contain telegraphic conductors, blocks constituting supports for the telegraphic conductors, and provided with openings for the passage of air, of an outer box or trough and a layer of pitch or analogous material between the boxes or troughs.

The improvement also consists in the combination, with a wooden box or trough adapted to contain telegraphic conductors, blocks constituting supports for the telegraphic conductors, and provided with openings for the passage of air, of an outer box or trough, a layer of pitch or analogous material between the boxes or troughs, and a layer of pitch or analogous material on the exterior of the outer box or trough.

The improvement also consists in the combination, with a box, trough, or pipe, telegraphic conductors arranged therein, and supports for the telegraphic conductors, provided with openings for the passage of air, of means

for causing air to circulate through the box, trough, or pipe, and means for drying the air before its entrance into the box, trough, or pipe.

In the accompanying drawings, Figure 1 is 55 a longitudinal section of an apparatus embodying my improvement, and Fig. 2 is a transverse section of the same.

Similar letters of reference designate corresponding parts in both figures. 60

A designates a box, trough, or pipe, which may be made of wood and of a square cross-section. At suitable intervals it is provided with blocks B, which may be made of wood or other suitable material. These blocks are perforated so as to receive and support telegraphic conductors C. The said blocks are arranged sufficiently near together to prevent the telegraphic conductors from accidentally touching each other. As shown, the corners of the 70 blocks are cut off so as to leave spaces a, through which air may pass. The blocks are also provided with central openings, b, which likewise afford provision for the circulation of air past them. The box, trough, or pipe A is 75 inclosed in a larger box, trough, or pipe, D, which may be of the same material and construction. A layer of pitch or analogous material, E, is interposed between the two boxes, troughs, or pipes A D, and a layer of like material, G, is applied to the exterior of the box, trough, or pipe. The box, trough, or pipe A is practically water-proof and moisture-proof. In order to prevent the moisture in the atmosphere from condensing within this box, trough, 85 or pipe, or the collection of moisture there from any source, I circulate air through the same, either constantly or at desired intervals. Any suitable means may be employed for this purpose—as, for instance, a pump or blower; 90 but I prefer generally to employ a chimney, stack, or flue. I have shown a chimney, H, communicating with the box, trough, or pipe A for this purpose. This induces a circulation of air through the pipe from the other end. 95 A fire, lamp, or other source of heat will be kept in the chimney to induce or stimulate an upward draft. In lieu of or in addition to this, a cap or cowl may be employed to induce or stimulate an upward draft. In many cases a 100 chimney connected with a furnace used for manufacturing purposes or some industry can-

be utilized for inducing a draft through the box, trough, or pipe A. If the atmosphere is moist, as it is continuously in many places and at times in all places, I shall preferably 5 dry the air before circulating it through the box, trough, or pipe A. This may be done by chemicals or by heat. I have shown a furnace, 1, for heating it. The air passes through this furnace, and is heated and dried before entering the box, trough, or pipe A. The air may 10 be dried by cooling it before its entrance into the box, trough, or pipe A.

This improvement is particularly designed 15 for telegraphic conductors to be laid under ground.

What I claim as my invention, and desire to secure by Letters Patent, is—

1. The combination, with a box, trough, or pipe, telegraphic conductors arranged therein, 20 and supports for the telegraphic conductors, provided with openings, of means whereby air may be caused to circulate through the box, trough, or pipe, substantially as specified.

2. The combination, with a number of tele- 25 graphic conductors, of a box, trough, or pipe containing the said conductors, a number of supports for the said conductors, arranged within the box or trough or pipe, openings being provided in the supports and between the 30 supports and the box or trough or pipe for the circulation of air, and means whereby air may be caused to circulate through the box, trough, or pipe, substantially as specified.

3. The combination, with a wooden box or trough adapted to contain telegraphic conductors, blocks constituting supports for the telegraphic conductors, and provided with openings for the passage of air, of an outer box or trough and a layer of pitch or analogous material between the boxes or troughs, substan- 35 40 tially as specified.

4. The combination, with a wooden box or trough adapted to contain telegraphic conductors, blocks constituting supports for the telegraphic conductors, and provided with openings for the passage of air, of an outer box or trough, a layer of pitch or analogous material between the boxes or troughs, and a layer of pitch or analogous material on the exterior of the outer box or trough, substantially as speci- 45 50 fied.

5. The combination, with a box, trough, or pipe, telegraphic conductors arranged therein, and supports for the telegraphic conductors, provided with openings for the passage of air, 55 of means for causing air to circulate through the box, trough, or pipe, and means for drying the air before its entrance into the box, trough, or pipe, substantially as specified.

JAS. H. GREEN.
